FRANZ A. BOEDTCHER, OF BERGENFIELD, NEW JERSEY.

ELEVATOR-DOOR LOCK.

1,350,698.

Specification of Letters Patent. Patented Aug. 24, 1920.

Application filed January 17, 1919. Serial No. 271,615.

To all whom it may concern:

Be it known that I, FRANZ A. BOEDTCHER, a citizen of the United States, residing in Bergenfield, county of Bergen, and State of New Jersey, have invented a certain new and useful Elevator-Door Lock, of which the following is a specification.

This invention is an elevator door lock and is intended, more particularly, for use 10 on shaft doors or gates of elevators. In a normal operation of shaft doors the elevator operator is apt to become rather careless in the closing of the doors at the various floors, and it is not infrequent that these 15 doors are slammed shut so violently that they rebound into partially open position before latches, normally employed to lock them shut, can come into effective operation. As a result the car, as it proceeds 20 upon its way, leaves the door slightly open, with the result that a dangerous condition exists. Children are apt to stray through the opening and fall through the shaft, or curious persons waiting at that particular 25 floor for the next passage of the car not infrequently stick their heads through the opening just in time to be struck by the passing car. Accordingly, in many cities, the laws provide for certain safety appliances intended to obviate the occurrence of 30 accidents of the character specified.

In view of the foregoing, means, generally electric, are usually provided for precluding the movement of the elevator car 35 away from a floor, unless the shaft door at said floor is previously closed and locked.

The present invention, however, overcomes the foregoing disadvantages by purely mechanical means adapted to insure 40 the locking of the door in a fully closed position, or, if the door should slightly open due to a sharp rebound, it will be locked in such partially open condition so that further opening of the door is impossible.

The object of the present invention, is, therefore, to provide a simple mechanical expedient for locking a door in fully closed position, as well as in any intermediate position between those of fully opened and 45 fully closed.

Features of the invention other than those specified, will be apparent from the hereinafter detailed description taken in conjunction with the accompanying drawings.

In the accompanying drawings, I have

illustrated one practical form of the invention, but the construction shown therein is to be understood as illustrative only, and not as defining the limits of the invention. 60

Figure 1 is a view of the interior of an elevator shaft, showing just a sufficient fragment of the same to illustrate the application of the present invention thereto. In this figure the door casing of a floor 65 door is shown; the door is shown in fully opened position;

Figs. 2, 3 and 4 are fragmental views, similar to that of Fig. 1, but illustrating the mechanism of the present invention in different operative positions. 70

Referring to the drawings, A designates the casing of an elevator shaft door which is normally closed by means of a sliding door or gate B, mounted and actuated in 75 any suitable manner. The door is here shown of sliding type. The means for operating the door are immaterial to the present invention, and, accordingly, are omitted in the interest of clearness. 80

Mounted on the upper inner surface of the door, and preferably adjacent the forward edge thereof, is a gravity latch C, pivoted at c and weighted at c' so that it will normally gravitate into the position 85 shown in Fig. 1, wherein the nose of the latch protrudes above the upper edge of the door. On the casing A is a locking plate D, here shown as embodying a metal plate bent at two right angles and secured to the casing by bolts or lag screws d'. The plate D has a depending flange d² in the lower edge of which is formed consecutive serrations d, so that said edge is of a saw-tooth configuration. The plate D is so proportioned that the saw-tooth edge of the flange d² will lie in the path of the latch C, mounted on the door, and these parts are adapted to coöperate with one another for the purpose of automatically locking the door 90 against retrograde movement after the same has been closed. The flange d² may be of any length desired, but is preferably sufficiently extensive to lock the door from a position wherein it is fully closed to any 95 position up to an opening of say one foot. 100

With this construction, it will be apparent that if an operator slams a door shut so violently that the latch cannot operate to lock the door fully shut, it cannot rebound to an open position as the latch will engage 110 with one of the adjacent serrations d and

lock the door against further opening. However, in practice, it is found that, since the latch during the closing operation of the door is in contact with the serrations and 5 riding idly thereover, it will invariably engage the first serration and will lock the door in closed position. Moreover, if the operator gives the door insufficient impetus to entirely close it, it will be locked in its 10 foremost advanced position and cannot be opened from the corridor side of the shaft. In fact, it can only be released from the shaft side by the means next to be described.

The weighted portion *c'* on the latch *C* is 15 preferably in the form of a flange projecting below the body portion of the latch, and this flange is availed of a guide for the operations of the latch relative to a link *E* by which it may be manually operated by the elevator 20 attendant. The link *E* is pivoted at *e* at one of its ends and at its other end has pivoted connection with a push rod *F*, with the lower end of which is associated an operating handle *G*.

25 In the normal operation of the device, the door, when in open position, to allow of the entrance or exit of passengers from the car, is as shown in Fig. 1, the latch *C* being removed from locking plate *D*, and the weighted end of said latch is supported on the link *E*. When the door is moved to the closed position, the latch will ride idly over the saw-tooth edge of the locking plate after the manner shown in Fig. 4, until the door comes 30 to its closed, or partially closed position, at which time the latch will engage with one of the serrations *d* shown in Fig. 2. The parts will remain in these relative positions until the elevator operator desires to reopen 35 the door through the manual forcing down of the handle *G*, at which time the link *E* will be tilted up for the purpose of rocking the latch on its pivot *e* free from engagement with the locking plate as shown in 40 Fig. 3, at which time unobstructed retrograde movement of the door may be had.

45 While the door locking means hereinbefore described has been referred to as entirely independent of the door closing and opening devices, said door may, nevertheless, be opened and closed through the grasping of the handle *G* by the operator and his bodily movement of the door through this medium. In fact, the handle *G* may partake 50 various forms, so long as it fulfills the function of operating the push rod *F*.

55 The use of a pawl and ratchet arrangement on elevator doors is not broadly new, but in all the prior constructions, these parts 60 were so arranged that it was impossible to lock the door in a fully closed position through the employment of these elements, and a separate and independent locking means had to be provided to lock the door 65 fully closed. The function of the pawl and

ratchet devices heretofore employed have been merely to lock the door in a partially open position, in case the door had not been fully closed, the mere act of fully closing the door, automatically rendering the pawl and 70 ratchet arrangements, inoperative as a locking medium. The present invention provides unitary means for locking the door in either closed or partially closed position and entirely obviates the necessity of separate 75 and independent locking means, such as has heretofore universally been the case.

What I claim as new and desire to secure by Letters Patent is:

1. An elevator door lock embodying a serrated member adapted to be secured to a door casing, a coöperating gravity latch pivoted on the door associated with said casing, and adapted to normally gravitate into engagement with one of the serrations of said member, when the door is in closed or partially closed position, to lock the same against retrograde movement, a manually operable push rod, and a member for operatively associating the push rod with the 90 latch, said member serving to normally maintain the latch in a position to engage with the serrated member to lock the door in closed or partially closed position, and being operable by the push rod to shift the latch 95 against gravity free from the serrated member to unlock the door and allow of the opening thereof.

2. An elevated door embodying a serrated member adapted to be secured by a door 100 casing, a coöperating pivoted gravity latch on the door associated with said casing, and adapted to normally gravitate into engagement with one of the serrations of said member when the door is in closed or partially closed position to lock the same against retrograde movement, a pivoted member for limiting the pivotal movement of the latch under the force of gravity, to a position wherein it will normally coöperate 105 with the serrated member, and manually operable means associated with the pivoted limiting member for actuating the same to oscillate the latch against the force of gravity out of coöoperative relation with the serrated member.

3. An elevator door lock embodying a serrated member adapted to be secured to a door casing, a latch pivoted on the door associated with said casing, a link for manually actuating said latch, said latch being provided with a flange serving to maintain the latch and link in coöoperative relation and simultaneously normally causing the latch to gravitate into coöoperative relation 115 with the serrated member when the door is in closed or partially closed position to lock the same and a manually operated push rod associated with the link for moving the latch, against the force of gravity, into a 120

125

130

position free from engagement with the serrated member to allow of free opening of the door.

4. An elevator door lock embodying a serrated member adapted to be secured to a door casing, a latch pivoted on the door associated with said casing, a link for manually actuating said latch, said latch being provided with a flange serving to maintain the latch and link in coöperative relation and simultaneously normally causing the latch to gravitate into coöperative relation with the serrated member when the door is

in closed or partially closed position to lock the same, a push rod for operating said link 15 and a manually operated handle associated with the push rod, whereby the operations of the handle are transmitted through the push rod and link to oscillate the latch into a position wherein it is free from engagement with the serrated member for the purpose of allowing free opening of the door.

In testimony whereof I have signed my name to this specification.

FRANZ A. BOEDTCHER.
